UNITED STATES PATENT OFFICE.

LIBANUS M. TODD AND JOHN J. LEARY, OF ROCHESTER, NEW YORK,
ASSIGNORS TO THE LOEWER SOLE-ROUNDER COMPANY, OF SAME
PLACE.

SOLE-ROUNDING MACHINE.

SPECIFICATION forming part of Letters Patent No. 558,004, dated April 7, 1896.

Application filed December 5, 1895. Serial No. 571,169. (No model.)

To all whom it may concern:

Be it known that we, LIBANUS M. TODD and JOHN J. LEARY, citizens of the United States, residing at Rochester, in the county of Monroe and State of New York, have invented a new and useful Improvement in Sole-Rounding Machines, of which the following is a specification.

This invention relates to an improved stock-gage for use upon sole-rounding machines of the class which work upon block-stock, and more especially upon machines of this class known as "rotary-knife" machines in which the block-stock is turned in accordance with a pattern and shaped by the action of the rotary knives.

The improvement as illustrated in the accompanying drawings is designed more especially for use upon the Loewer sole-rounding machine, Patent No. 502,421, dated August 1, 1893. In this machine the pattern and block-stock to be cut are held between clamps to revolve on a swinging frame and upon the same axis. Adjacent thereto is a rotary shaft carrying cutter-knives and a guide-roller, the operation being performed by the rotation of the pattern upon the guide-roller, whereby the swinging frame is moved to change the position of the stock with relation to the cutter-knives.

Block-stock, for the sake economy, is usually cut to a size but little larger than the sole which it is intended to form therefrom, and for this reason it is necessary that the stock shall be positioned in the machine with great exactness. Hitherto it has been usual to employ a stock-gage which was adjustable according to the pattern after the latter had been placed in the machine, and while such stock-gages have been more or less satisfactory in operation so far as the positioning of the stock was concerned they rendered the operation of positioning slow to accomplish. The present object is to provide a stock-gage which may be adjusted with reference to the pattern, but without contact therewith, and according to a scale which may be readily followed, whereby the adjustment may be effected very quickly and the speed of operation thus greatly increased. In carrying out the

invention it is preferred to follow a system which involves providing the patterns with holes, at which they are fastened in the machine, positioned in accordance with a scale corresponding with a scale or scales upon the stock-gage, all as will be fully described later on.

The drawings show the improved stock-gage in two forms, the main points of difference being that one employs gage-adjusting mechanism operated by swinging levers and the other gage-adjusting mechanism operated by turning levers or screws.

In the drawings, Figure 1 is a front elevation of a sole-rounding machine of the Loewer type with the improved stock-gage of the first-said form applied thereto; Fig. 2, an enlarged section taken on line 2 of Fig. 1 and viewed in the direction of the arrow; Fig. 3, an enlarged section taken on line 3 of Fig. 1 and viewed in the direction of the arrow; Fig. 4, an enlarged broken section of a pattern-clamp; Fig. 5, a plan section taken on line 5 of Fig. 3; Fig. 6, a sectional view showing a detail of the construction, the section being taken on line 6 of Fig. 7; Fig. 7, a broken section taken on line 7 of Fig. 6; Fig. 8, a broken section of a rod forming a detail of the construction and marked with a scale; Fig. 9, a plan view of a sole-pattern; Fig. 10, a view in elevation of the improved stock-gage of the second said form; Fig. 11, an enlarged broken section taken on line 11 of Fig. 10; Fig. 12, a plan section taken on line 12 of Fig. 10; Fig. 13, an enlarged section taken on line 13 of Fig. 12; Figs. 14 and 15, enlarged and broken sections taken, respectively, on lines 14 and 15 of Fig. 10; Fig. 16, a plan section taken on line 16 of Fig. 10, and Fig. 17 an enlarged broken elevation of one side of the detail shown in Fig. 16.

As the improvement in either form is mounted upon the vibrating carriage or swinging frame of the machine only that much of the machine is illustrated in the drawings, for the reason that the construction and operation of the rotary cutters and other parts are well known in the art.

A is a part of the main frame of the machine, and B the vibrating carrier or swing-

ing frame, pivotally mounted at its lower end upon a shaft t . Journalized in the frame B is a shaft comprising sections C, C', and C². On the outer end of the section C is a drive-wheel 5 s, which may be an ellipsoid, as shown in the aforesaid Loewer patent, and upon the inner end of the same section is the member r of a pattern-clamp D. The shaft-section C' slides longitudinally in its bearings and is provided 10 at one end with the member r' of the clamp D and at its opposite end with the member q of a stock-clamp E. The shaft-section C² is provided at its inner end with the member q' of the clamp D and is adapted to be 15 moved longitudinally in its bearing by the turning of a hand-wheel x . The members of the clamp D are provided with smooth flat clamping-faces, and on the member r are pins r^2 r^2 , which occupy a certain predetermined 20 position and enter sockets r^3 r^3 in the member r' . On the shaft-section C' is a suitable spring p , which tends to press the member r' against the member r .

Referring first to the construction of the 25 stock-gage shown in Figs. 1 to 8, inclusive, on the frame B, in the position shown, is a boss or bracket n , from which extends a bar n' , which may be square in cross-section, as shown. Fitting and sliding upon the bar n' 30 is a sleeve m , forming a part of the supporting-frame of the stock-gage F. Fastened upon the frame B, toward the upper end of the latter, is a segmental bar or yoke l . Pivoted at its lower end to a bracket l' on the 35 frame B is a lever m' , pivotally connected between its ends at m^2 to the sleeve m and at its upper end sliding along the segmental bar l . On the lever m' at the bar l is a bracket m^3 , which extends over the bar l and is provided with a clamp-screw m^4 , which may be 40 turned to engage the bar l and hold the lever m' in adjusted position. While a clamp-screw m^4 is shown for fastening the lever m' against movement upon the bar l , any other 45 suitable fastening means may be employed. On the sleeve m , and forming an integral part thereof, is a sleeve m^5 , extending at right angles to the sleeve m and provided through it with an opening m^6 . Integral with the 50 sleeve m^5 is a sectoral plate m^7 , provided with a segmental slot m^8 in the arc of a circle of which the sleeve-opening m^6 is the center. Extending through the opening m^6 is a bar k . Fixed to the bar k , above the sleeve m^5 , is a 55 collar k' , and also fixed to the bar k , below the sleeve m^5 , is a sleeve k^2 , carrying an arm k^3 . Pivotally mounted in the outer end portion of the arm k^3 is a catch k^4 , and at the peripheral edge of the plate m^7 , on the under 60 side thereof, is a flange m^9 , provided with notches m^{10} m^{11} in the positions indicated in Fig. 1. The collar k' and sleeve k^2 prevent longitudinal movement of the bar k in the sleeve m^5 , but permit it to be rotated between 65 the two positions wherein the catch k^4 engages the notches m^{10} m^{11} . On the upper end

of the bar k is an arm k^5 , and at the lower end thereof is an arm k^6 , which extends parallel with the arm k^5 . Fastened at its upper and lower ends, respectively, in the arms k^5 ⁷⁰ k^6 is a guide-rod k^7 , which extends parallel with the bar k and passes through the segmental opening m^8 in the plate m^7 and through an opening in the arm k^3 .

On the lower end portion of the bar k is an ⁷⁵ arm i , having a sleeve portion i' , which surrounds and slides upon the bar k , a sleeve portion i^2 , which surrounds and slides upon the guide-rod k^7 , and an upward-extending finger portion i^3 . Adjustably secured to the ⁸⁰ finger i^3 is a lower gage member or gage-plate i^4 , having a downward-extending finger i^5 , which is attached to the finger i^3 by means of a clamp-screw i^6 . The gage-plate i^4 may be raised and lowered with reference to the arm ⁸⁵ i by loosening the clamp-screw i^6 and may be fastened in adjusted position by tightening the set-screw. At the sleeve i' is a yoke i^7 , provided with openings to receive the bar k on opposite sides of the sleeve and slide with ⁹⁰ the said sleeve upon the bar. Sliding upon the bar k above the arm i is an arm h , having a sleeve portion h' , which surrounds the bar k , a sleeve portion h^2 , which slides upon the guide-rod k^7 , and an upward-extending finger ⁹⁵ h^3 , bent to a right angle at its upper end portion. Adjustable upon the finger h^3 is a gage member or middle stock-gage h^4 , mounted upon a finger h^5 , secured to the finger h^3 by means of a thumb-screw h^6 . The finger h^5 ¹⁰⁰ may be slid longitudinally upon the finger h^3 to a limited extent and fastened in adjusted position by means of the thumb-screw h^6 . At the sleeve portion h' of the arm h is a yoke h^7 , having openings through it to receive and ¹⁰⁵ slide upon the bar k at opposite sides of and with the said sleeve. Above the plate m^7 is an arm g , having a sleeve portion g' , which surrounds and slides upon the bar k , a sleeve portion g^2 , which fits around and slides upon the guide-rod k^7 , and a bent finger g^3 . Mounted upon the finger g^3 is a gage member or upper stock-gage g^4 , having an arm or finger g^5 , which is adjustably secured to the finger g^3 by means of a thumb-screw g^6 . The finger g^5 ¹¹⁰ may be slid to a limited extent upon the finger g^3 and fastened in adjustable position by means of the thumb-screw g^6 . At the sleeve portion g' is a yoke g^7 , having openings through it to receive and slide upon the bar k on opposite sides of and with the said sleeve. Fulerumed at y upon the stationary sleeve m^5 is a lever f , connected at its long arm, through the medium of a link f' , with the yoke i^7 . A link f^2 connects the lever f , between the link ¹¹⁵ f' and fulcrum y , with the yoke h^7 . The link f^2 is in two overlapping parts, which slide upon each other and are held together by means of a screw f^3 , thus rendering it possible to shorten or elongate the lever, as desired. A link f^4 connects the short arm of the lever f with the yoke g^7 . The link f^4 is ¹²⁰ ¹²⁵ ¹³⁰ ¹³⁵

also constructed to be lengthened and shortened, as desired, it being formed of overlapping sections held together by a screw r^5 .

In the sole-rounding machine shown in Fig. 5 1 of the drawings the member r' of the pattern-clamp D and the member q of the stock-clamp E are in rigid relation and extend in the same plane. When the machine is started, it rotates the member r of the pattern-clamp 10 one complete revolution and then stops, and the driving mechanism is so arranged that the member r , its companion member r' , and the stock-clamp will always stop at a certain fixed position, in which position the pins r^2 15 are at a slight angle to the vertical plane. The patterns Z employed in the machine are preferably, though not necessarily, of sheet metal and provided with openings $z z'$, which, as it is preferred to provide them, are located 20 in the ball and heel portions, as shown in Fig. 9. The openings $z z'$ register exactly with the pins r^2 , and while the location of the said pins may be changed, if desired, it is necessary that each pattern used with the machine shall 25 have openings $z z'$ which conform exactly in location with the pins. The pattern is placed in position in the machine before the stock Y is inserted, and this is accomplished by moving the clamp member r' to the right in Fig. 30 1 against the resistance of the spring p to permit the placing of the pattern upon the pins r^2 . The clamp is closed by the resiliency of the spring p , whereby the pattern is held firmly between the members $r r'$. The 35 stock Y, known as "block-stock," and previously cut to a shape more or less nearly approximating that of the pattern, is placed in position by opening the clamp E, which is done by turning the wheel x in one direction, 40 and fastened in place by turning the wheel x in the opposite direction. The pressure exerted by the clamp member q against the stock and through the latter against the clamp member q and clamp D holds the parts 45 firmly together, whereby in the rotation of the drive-wheel s they will all turn together. As before stated, it is necessary that in placing the stock in the clamp E it shall be so positioned with relation to the pattern that the 50 rotary cutters may act more or less upon the entire edge portion of each blank or individual piece of block-stock.

In practicing our invention we prefer to follow a certain system, which may be briefly 55 described as follows:

The machine, it will be understood, is capable of operating upon both insoles and outsoles of all sizes and shapes. Having established a standard for the position of the pins 60 r^2 according to two, or perhaps three, widely-varying sizes, which standard will be preferably common to all machines, each pattern Z will be provided with holes $z z'$, which will register exactly with the pins. It may be 65 stated that in practice the upper pin r^2 in Fig. 4, which is the pin intended to be engaged by the openings z of all the patterns,

will always be provided at a certain fixed distance from the center of rotation of the shaft-sections C C'. For patterns of large size, 70 such as those for men's shoes, a clamp D would be provided, having the lower pin r as far or farther from the center of rotation of the shaft-sections than the upper pin r^2 . For the patterns of small-sized soles, as for children's shoes, the lower pin r^2 may be near the center of rotation of the shaft-sections C C'. 75 In practice not more than two or three different clamps D need be provided for a machine, the larger patterns used having holes $z z'$ to 80 fit the pins of the larger clamp and the smaller patterns having holes $z z'$ to fit the pins of the smaller clamp.

The stock-clamp E should be of a size, especially when working upon insoles, nearly 85 approximating the size of the pattern, in order that it may hold the stock as nearly as convenient to the edge portion of the latter while it is being operated upon by the cutters. In practice one clamp E will do, especially 90 when the machine is working upon flexible insoles, for but a limited number of sizes, both with relation to length and width.

It is necessary in positioning the stock in the clamp E provided that the stock shall project more or less from all sides of the clamp and be in such position in the clamp that in its movement in accordance with the pattern the cutters will cut more or less from all sides of the stock and the clamp will never come 100 into contact with the knives. For this reason it is desirable in practice to provide the holes $z z'$ of patterns Z of different sizes at different distances from the inner edge, which is the edge z^2 of the pattern, the holes being 105 each at an equal distance from the farthest projecting portions of the said inner edge at the ball and heel portions of the pattern. In other words, the holes $z z'$ should be equidistant from the dotted straight line shown 110 in Fig. 9. In practicing the said system the holes $z z'$ of each pattern are punched at equal distances from the inner edge of the pattern, varying, as may be desirable, according to the width and shape of the pattern, by stages of one-sixteenth of an inch, and on each pattern the distance is marked, 115 as shown at the top of the pattern in Fig. 9, where the numeral "XIV" indicates that the holes $z z'$ are fourteen-sixteenths of an inch 120 from the inner edge. The pattern Z is so placed in the clamp D that the inner edge z^2 is toward the operator or front of the machine. On the segmental bar l is a scale l^2 , marked with numerals indicating sixteenths of an 125 inch, and the lever m' carries a pointer m^2 , which in the movement of the lever registers with the scale. Thus according to the numeral marked thereon the lever m' may be swung to move the stock-gage frame toward or away from the vertical plane of the center of rotation of the shaft-sections C C', and therefore toward and away from the plane 130 of the pins r^2 .

In positioning the stock in the clamp E it is located with relation to three points of the pattern—namely, the point z^3 at the lowest part of the heel-seat, the point z^4 or farthest 5 projecting inner edge portion of the heel-seat, and the point z^5 or farthest projecting part of the inner edge of the ball portion. The lower gage member i^4 is intended to position the lower end of the stock with relation to 10 the point z^3 of the pattern, the middle gage member h^4 to position the stock with relation to the point z^4 of the pattern, and the gage member g^4 to position the stock with relation to the point z^5 of the pattern, a slight allowance in practice being provided for at all 15 three said points to cause the cutters to work upon the material at those parts. The three gage members $i^4 h^4 g^4$ are upon sliding supports, as before described, all of which connect, by means of the links described, with the lever f , and their link connections are such that the member i^4 will be moved a greater distance in the movement of the lever than either the member h^4 or g^4 .

25 In practice the patterns for soles of different sizes will vary in length to a much greater degree than they will in the matter of the distances between the points $z^3 z^4$, which mark the points of farthest protuberance at the end 30 and inner edge of the heel-seat, and the parts of the gage are so connected with the lever that the movement of the gage members will approximate the variations of the three points $z^3 z^4 z^5$ in the different sizes and shapes. Pivotally connected at its lower end to the pin i^4 on the yoke i^4 is a rod e , which passes upward loosely through a plate or bracket e' on the sleeve m^5 . On the said plate or bracket is a finger e^2 , presenting two shoulders e^3 and 35 e^4 , respectively, affording pointers. Marked upon the rod e is a scale e^5 , indicating sizes, and the gage members are so mounted with relation to the lever f and scale e^5 that when the rod is moved by the action of the lever to 40 register at, say, the line marked "1" in Fig. 8 with the pointer e^4 the gage members will be in position to conform to the points $z^3 z^4 z^5$ in accordance with the pattern of a No. 1 outsole. By raising the lever until the figure 45 "1" on the scale e^5 registers with the pointer e^3 the gage members will be in position to position the stock in conformity to the points $z^3 z^4 z^5$ of the pattern for a No. 1 insole.

As is well known in the art, two separate 50 sets or series of the same numbers are generally employed to designate the sizes of lasts, one relating to children's shoes and the other to those of adults, and the rod e and segmental bar l would be provided, preferably, with 55 two scales conforming to the two series mentioned.

In operation when soles of a certain size are to be rounded the operator selects the pattern, noting at the same time the figure at 60 the top, before mentioned. His first operation will be to move the lever m' , if necessary, to cause the pointer m^{12} to register with the

proper numeral on the scale l^2 , corresponding with the said numeral on the pattern. The lever m' may be then secured in adjusted position by turning the thumb-screw m^4 . The operator will then move the lever f until the proper number in the scale e^5 on the rod e registers with the pointer on the finger e^2 . If he is to cut insoles, he will select the pointer e^3 , and if he is to cut outsoles he will select the pointer e^4 . When the parts are thus adjusted, they may be fastened against displacement by tightening a thumb-screw g^8 in the sleeve portion g^2 , which is adapted to engage the rod k^7 . The adjustment may be effected while the latch k^4 is in engagement with the notch m^{10} , and the frame consisting of the rod k , arms $h i g$, and gages carried thereby is swung out of the way. After the adjustment 85 the said frame is swung to the position wherein the latch engages the notch m^{11} , as shown in Fig. 1, which places the gage members in the proper location to position the stock. The stock is placed in the clamp E 90 and caused to rest at its heel portion upon the gage member i^4 and bear at its inner edge portion against the gage members $h^4 g^4$. When the stock is positioned, the stock-clamp is first closed and the gage-carrying frame 95 then swung out of the way. The stock is thus in position to be operated upon by the rotary cutters in the usual manner.

In case that for any reason the block-stock from which soles are to be formed shall have 100 a materially different shape from the pattern—as, for example, a materially greater concavity or sweep at the shank than the pattern—it may be desirable to position the stock in the stock-clamp with due allowance for 105 such variations. This may also be the case when, as it sometimes happens, the stock is to be cut full or larger than the pattern. Any such variation from standard requirements may be effected in this improved stock-gage 110 and still cause the gage members to be properly positioned by movement of the levers m' and f with reference to the scales by adjusting the fingers which carry the gage members on their supports, as before described, to withdraw one or another of the gage members to the 115 desired extent from the position it would occupy under standard requirements.

If desired, the supporting-finger for each gage-carrying finger may be suitably marked, 120 as at $y' y'$ in Fig. 2, to indicate the positions that the ends of the latter should occupy with reference to the former under standard requirements.

In the construction shown in Figs. 10 to 16, 125 inclusive, d is a sleeve adapted to fit and slide upon the preferably-squared bar or shaft n' , before mentioned, and which forms the sole-support of the gage-frame. The sleeve d at its outer end portion is formed into a yoke d' , 130 having a threaded opening d^2 in its outer end to receive a threaded rod c , provided with a handle c^5 . The inner end of the rod c is reduced, as shown at c' in Fig. 14, and there

enters a socket d^8 in the end of the bar n' . The reduced portion c' is provided with a circumferential recess c^2 , which is crossed by a pin c^3 , extending through the bar n' . Thus 5 the rod c may rotate in the socket d^8 , but is held to the bar by the pin c^3 . Rotation of the rod c by means of its handle c^6 will move the sleeve d upon the said bar, and a gage c^4 is provided upon the bar, as shown in Fig. 12, 10 for a purpose hereinafter described. Integral with or in fixed relation to the sleeve d and extending at right angles thereto is a sleeve d^4 , provided through it with a smoothly-bored opening d^5 .

15 Extending through the opening d^5 and confined therein to rotate freely, but without longitudinal play, is a rod or shaft b , provided along its lower end portion with screw-threads b' of one pitch, between the threads b' and 20 sleeve d^4 with a screw-thread b^2 of another pitch, and above the sleeve d^4 with a screw-thread b^3 of still another pitch. The thread or threads b^3 extend in one direction and the threads $b' b^2$ in the opposite direction, and in 25 practice it is preferred to provide a screw b' with a lead of about six threads to the inch, a screw b^2 with a lead of about nine threads to the inch, and a screw b^3 with a lead of about twenty-five threads to the inch.

30 Pivotedly mounted upon the upper and lower end portions of the shaft b are parallel arms $b^4 b^5$, respectively, to which is secured at opposite ends a guide-rod b^6 , extending parallel with the shaft b . On the upper end 35 of the shaft b and fixed thereto is a crank b^7 , provided in its free end portion with a catch in the form of a spring-controlled pin b^8 , provided at its upper end with a handle b^9 and tapered at its lower end b^{10} to engage a 40 socket b^{11} in the upper end of the rod b^5 , as shown in Fig. 11. The arm a , carrying the lower gage member a' , has a threaded opening through it to travel upon the screw b' and is bored in proper location to slide upon the rod b^6 . The arm a^2 , carrying the middle gage member a^3 , has a threaded opening through it to receive and travel upon the screw b^2 , and the arm a^4 , carrying the upper gage member a^5 , 45 has a threaded opening through it to receive and travel upon the screw b^3 . The arms $a^2 a^4$ are provided with openings to receive and move upon the rod b^6 . Marked upon the rod b^6 , preferably at the arm a , is a gage b^{12} , and the arm a may carry insole and outsole pointers b^{13} , as shown in Fig. 10. Fixed upon or 50 formed integral with the sleeve d^4 is a plate d^6 , having a segmental upward-extending flange d^7 , provided on its upper edge at one end portion with a spring-catch d^8 . Integral 55 with the arm b^4 is a laterally-projecting finger b^{14} , which rides upon the upper edge of the flange d^7 , and when moved toward the position shown in Figs. 16 and 17 depresses the spring-catch d^8 . When it reaches the 60 position shown in those figures, it passes the spring-catch d^8 and bears against a stop d^9 , the end of the spring presenting a shoulder

which holds the finger against movement. The spring d^8 is provided with a projecting lip d^{10} , at which it may be engaged by the 65 operator and depressed to permit the finger b^{14} to be slid across it.

The bearings of the arms $a a^2 a^4$ at the screw-shaft B are split and may be compressed by means of the screws y^3 (shown in 70 Fig. 10) to compensate for wear. The sleeve d may also be split, as indicated in Fig. 12, and compressed by means of screws y^2 to fit snugly upon the bar n' . These split bearings being a common expedient in mechanics, it 75 is not thought necessary to illustrate them more fully or describe them more minutely. The lower gage member a' is provided on its under side with an internally-threaded sleeve-piece a^6 , at which it is screwed upon the arm 80 a , whereby it may be raised and lowered to adjust it with relation to the latter. When adjusted, it may be secured by means of a jam-nut a^7 . The plate forming the lower gage a' is preferably squared, so that it may 85 be adjusted by quarter-revolutions upon the arm a . The gage members $a^3 a^5$ are provided at their edges with threaded supporting pins or bolts a^8 , which pass through openings in the arms $a^2 a^4$. On each pin or bolt a^8 , on the 90 inner side of the respective arm, is a jam-nut a^9 and on the outer side of the arm is a thumb-nut a^{10} . By loosening the nuts the 95 gage members may be adjusted toward or away from their supporting-arms and fastened in adjusted position by means of the nuts $a^9 a^{10}$.

In operation the frame, consisting of the sleeve d and parts carried thereby, may be positioned in accordance with the numeral on 100 the pattern Z, as before described, by turning the crank c^5 with relation to the gage c^4 , the crank c^5 and threaded rod c being the equivalent in this respect of the lever m' and segmental bar l of the other construction. 105 To position the gage members in accordance with the pattern, the handle b^9 may be grasped and raised to withdraw the pin b^8 from the socket b^{11} and the crank b^7 turned to rotate the screw-shaft b in accordance with the gage 110 b^{12} , which corresponds with the gage e^5 in the other construction. The turning of the screw-shaft b in one direction causes the lower and middle gage members to be lowered the predetermined relative distances and the upper 115 gage member to be raised a predetermined relative distance. The bearing-sleeve d^4 and the screw-shaft b are in practice at an angle to the vertical plane the same as the bearing-sleeve m^5 and attendant parts in the other 120 construction, whereby the tendency of the frame, consisting of the screw-shaft, arms $b^4 b^5$, rod b^6 , gage members, and their supporting-arms, is to swing away from the stock-engaging position. In moving the frame to 125 the stock-engaging position the finger b^{14} slides upon the segmental flange d^7 until it passes and is engaged by the spring d^8 , whereby the parts are locked in the stock-engaging 130 position.

position. Before the machine can be started to turn the stock against the rotary cutters the said frame must be swung out of the way of the rotating stock, and this may be accomplished by simply depressing the spring d^8 to release the finger b^{14} , when the frame will swing by gravity out of the path of the stock. In the Loewer sole-rounding machine automatically-operating means are provided for moving the stock-gage out of the path of the stock when the machine is started, and, if desired, mechanism for the same purpose may be provided for releasing the stock-gage in the present constructions whereby it will move out of the way.

The main object which it is desired to accomplish in both the constructions shown and described is to afford means whereby the gage members may be quickly, readily, and accurately positioned without contacting with the pattern, to the end of effecting materially greater economy in the matter of the time required for the positioning operation and greater certainty under all conditions than has been possible in the use of stock-gages hitherto provided. The difference between the two constructions is purely mechanical, and, broadly considered, their operations are substantially the same. In minor particulars each construction may be said to have advantages in certain respects over the other. For example, in the construction first described the levers $f'm'$ may be moved approximately as quickly to effect a change of several numbers as a change of one number in the sizes of soles to be successively rounded, while in the construction last described one complete rotation of the screw-shaft b will effect a change of but one number, and the same may be said of the screw c . On the other hand, the construction last described possesses advantages over the construction first described, because when cutting soles commencing with, say, the largest size and then adjusting the machine by gradations for smaller sizes in regular rotation a single complete turn of the operating-crank will change the adjustment one size, and the operator need not refer to the scale each time the pattern is changed.

In practice, to change the gage members from one size pattern to another involves usually the movement of the lower gage member one-sixth of an inch, the upper gage member one twenty-fifth of an inch, and the middle gage member only one-ninth of an inch in the direction of movement of the lower gage member. Thus while a material change is effected in the relative positions of the upper and lower gage members the middle gage member moves but slightly with relation to the lower gage member. The movement of the upper gage member being but about one twenty-fifth of an inch with each operation in the construction shown, it is not necessary in practice that it should be moved with each adjustment of the lower gage members, but

only occasionally, as once for every two or more changes in the sizes of the patterns. For this reason, and because it is difficult to provide durable threads as fine as required at the screw b^3 , the upper gage member may have separate independent adjusting means instead of the fine screw b^3 , which adjusting means may in practice be operated to move the upper gage member only occasionally, as required. It is within the scope of this invention, therefore, to have three or more gage members, of which only two or more shall be independently and simultaneously movable to unequal distances.

While the mechanisms shown and described carry out the invention in a manner that is eminently satisfactory, the constructions are susceptible of modifications in the matter of details without departing from the spirit of the invention as defined by the claims.

What is claimed as new, and desired to be secured by Letters Patent, is—

1. In a stock-gage for sole-rounding machines, the combination of adjustable gage members for positioning the stock at the end of the heel and side of the ball portion, and adjusting mechanism for the said gage members operative to move the same simultaneously toward and away from each other, substantially as and for the purpose set forth.

2. In a stock-gage for sole-rounding machines, the combination of adjustable gage members for positioning the stock at the end of the heel and side of the ball portion, a scale on the gage, and adjusting mechanism movable in accordance with the said scale to move the said members toward and away from each other with reference to but without contacting with the pattern, substantially as and for the purpose set forth.

3. In a stock-gage for sole-rounding machines, the combination of gage members for positioning the stock at the end and side of the heel, a gage member for positioning the stock at the side of the ball portion, and adjusting mechanism operative to move the said heel-gages and the ball-gage simultaneously toward and away from each other, substantially as and for the purpose set forth.

4. In a stock-gage for sole-rounding machines, the combination of gage members for positioning the stock at the end of the heel and side of the ball portion, and adjusting mechanism operative to move the said gage members simultaneously but to unequal distances toward and away from each other, substantially as and for the purpose set forth.

5. In a stock-gage for sole-rounding machines, the combination of gage members for positioning the stock at the end and side of the heel portion, a gage member for positioning the stock at the side of the ball portion, adjusting mechanism operative to move the said heel-gage members and the ball-gage member simultaneously toward and away from each other, the movement of the said ball-gage member being less than the move-

- ment of said heel-gage members, substantially as and for the purpose set forth.
6. In a rotary-cutting sole-rounding machine, the combination with the revoluble stock and pattern clamping mechanism, of a gage consisting of adjustable gage members for positioning the stock at different points in the stock-clamp, the gage being provided with a scale with reference to which the gage members may, without contacting with the pattern, be adjusted to position the stock with reference to the pattern, substantially as described.
7. In a rotary-cutting sole-rounding machine, the combination with the revoluble stock and pattern clamping mechanism, of adjustable gage members for positioning the stock at different points in the stock-clamp, adjusting means for the said gage members operative to move them simultaneously to different distances, a scale on the gage with reference to which the said adjusting mechanism may be moved, whereby the gage members are adjusted with reference to the scale and without contacting with the pattern to position the stock with reference to the pattern, substantially as described.
8. In a stock-gage for sole-rounding machines, the combination of adjustable gage members for positioning the stock at different points, and adjusting mechanism for two or more said members operative to move the same simultaneously to unequal distances in accordance with a predetermined scale, substantially as and for the purpose set forth.
9. In a stock-gage for sole-rounding machines, the combination of adjustable gage members for positioning the stock at different points, adjusting mechanism operative to move the said members simultaneously toward and away from each other, the said gage members being connected together to move simultaneously into and out of the stock-engaging position, substantially as described.
10. In a stock-gage for sole-rounding machines, the combination of adjustable gage members for positioning the stock at different points, a scale on the gage with reference to which the gage members may, without contacting with the pattern, be adjusted to engage and position the stock with reference to the pattern, the gage members being connected together and movable simultaneously into and out of the stock-engaging position, substantially as described.
11. In a rotary-cutting sole-rounding machine, the combination with the revoluble stock and pattern clamps, of adjustable gage members for positioning the stock in the stock-clamp, adjusting mechanism for two or more said members operative to move the same simultaneously toward and away from each other to unequal distances in accordance with a predetermined scale, the gage members being connected together and movable simultaneously into and out of the stock-engaging position, substantially as described.
12. In a rotary-cutting sole-rounding machine, the combination with the sole and pattern clamping mechanism, of adjustable gage members for positioning the stock at the heel and side of the ball portion, a scale on the gage with reference to which the gage members may, without contacting with the pattern, be adjusted to engage and position the stock with reference to the pattern, gage-adjusting mechanism for moving the gage members simultaneously toward and away from each other, the gage members being connected together and movable simultaneously into and out of the stock-engaging position, substantially as described.
13. In a stock-gage for sole-rounding machines, the combination with a gage-supporting frame on the machine, of movable gage-carrying arms on the said frame, and adjusting mechanism operative to move the said arms toward and away from each other, the gages being independently adjustable upon their supporting-arms, substantially as and for the purpose set forth.
14. In a stock-gage for sole-rounding machines, the combination with a gage-supporting frame on the machine, of movable arms on the said frame carrying gage members for positioning the stock at different points, a scale on the machine with reference to which the arms may be moved, and the gage members, without contacting with the pattern, may be adjusted to engage and position the stock with reference to the pattern, the gage members being independently adjustable upon their supporting-arms, substantially as and for the purpose set forth.
15. In a rotary-cutting sole-rounding machine, the combination with the revoluble stock and pattern clamping mechanism, of a stock-gage support mounted upon the machine, adjustable gage members on the said support for positioning the stock at different points in the stock-clamp, the said support being adjustable toward and away from the axis of rotation of the said clamping mechanism, and a scale on the machine according to which the support may be adjusted with reference to but without contacting at its gage members with the pattern, substantially as and for the purpose set forth.
16. In a rotary-cutting sole-rounding machine, the combination with the revoluble stock and pattern clamping mechanism, of a stock-gage support mounted upon the machine, adjustable gage members on the support for positioning the stock at different points in the stock-clamp, a scale on the gage with reference to which the gage members, may, without contacting with the pattern, be adjusted to position the stock with reference to the pattern, the said support being adjustable toward and away from the axis of rotation of the said clamping mechanism, and a scale on the machine according to which the support may be adjusted with reference to, but without contacting at its gage members

with, the pattern, substantially as and for the purpose set forth.

17. In a rotary-cutting sole-rounding machine, the combination with the revoluble stock and pattern clamping mechanism, of a stock-gage support mounted upon the machine, relatively-adjustable gage members on the said support and movable thereon into and out of the stock-engaging position, a scale on the support according to which the gage members may be adjusted with reference to, but without contacting with the pattern, and adjusting mechanism for the support operative to move it with the gage members toward and away from the axis of rotation of the said clamping mechanism, substantially as and for the purpose set forth.

18. In a rotary-cutting sole-rounding machine, the combination with the revoluble stock and pattern clamping mechanism, of a stock-gage support mounted upon the machine, relatively-adjustable gage members on the said support and movable thereon into and out of the stock-engaging position, a scale on the support according to which the gage members may be adjusted with reference to, but without contacting with, the pattern, adjusting mechanism for the support operative to move it with the gage members toward and away from the axis of rotation of the said clamping mechanism, and a scale on the machine according to which the said support may be adjusted with reference to, but without contacting at its gage members with, the pattern, substantially as and for the purpose set forth.

19. In a stock-gage for sole-rounding machines, the combination of adjustable gage members for positioning the stock at the end of the heel and side of the ball portion, and mechanism connected with the said gage members and operative to move the same simultaneously toward and away from each other, substantially as and for the purpose set forth.

20. In a stock-gage for sole-rounding machines, the combination with the stock-clamp, of adjustable gage members for positioning

the stock at different points in the said clamp, and mechanism connected with the said gage members and operative to move the same simultaneously to unequal distances toward and away from each other, substantially as and for the purpose set forth.

21. In a stock-gage for sole-rounding machines, the combination with the stock-clamp, of adjustable gage members for positioning the stock at different points in the said stock-clamp, and lever mechanism connected with the said gage members and operative to move the same simultaneously to unequal distances toward and away from each other, comprising a rotary screw-shaft provided with screw-threads of different pitches, upon which the said gage members are, respectively, mounted to travel, substantially as and for the purpose set forth.

22. In a rotary-cutting sole-rounding machine, the combination with the revoluble stock and pattern clamping mechanism, of a stock-gage support mounted upon the machine, relatively-adjustable gage members on the said support for positioning the stock at different points in the stock-clamp, and rotary screw-lever mechanism for adjusting the support toward and away from the axis of rotation of the said clamping mechanism, substantially as and for the purpose set forth.

23. In a stock-gage for sole-rounding machines, the combination of a rotary screw-shaft b , provided with threaded portions b' b^2 b^3 of different pitches, stock-positioning gage members, and arms carrying the said gage members and mounted, respectively, upon the respective screw portions, substantially as and for the purpose set forth.
